UNITED STATES PATENT OFFICE.

ELIAS B. REQUA, OF JERSEY CITY, NEW JERSEY.

LANTERN.

SPECIFICATION forming part of Letters Patent No. 244,670, dated July 19, 1881.
Application filed May 21, 1881. (No model.)

To all whom it may concern:

Be it known that I, ELIAS B. REQUA, a citizen of the United States, residing at Jersey City, in the county of Hudson and State of New Jersey, have invented new and useful Improvements in Lanterns, of which the following is a specification.

This invention relates to certain improvements in lamps and lanterns; and it consists in a peculiar construction, arrangement, and combination of parts, whereby the flame is supplied with a uniform quantity of air without being affected by excessive drafts induced by sudden or rapid movements of the lantern, the excess of air above that required for proper combustion being removed through suitable flues, so as to cool the lamp-frame and decrease the danger of explosions, and a free escape for the products of combustion being also provided through a perforated dome attached to a cap-piece, which is secured by an attachment and catch of novel construction, as hereinafter more fully set forth.

In the accompanying drawings, which fully illustrate the invention, Figure 1 is a vertical section. Fig. 2 is a bottom view. Fig. 3 is a view of the lamp fount and burner, partly broken away to show the relation of the parts. Fig. 4 is a view of the flanged wick-tube. Fig. 5 shows longitudinal and transverse sections through the burner-cone. Fig. 6 is a horizontal section through domed cap-piece. Fig. 7 is a view of the hinge attachment of the cap-piece; and Fig. 8 is a view of the hasp and spring-catch by which the cap-piece is secured to the frame.

A indicates the base of the lantern, which is concavo-convex in form and provided near its upper edge with perforations *a a*, that are arranged for the passage of air to the space below the fount when the lantern is resting upon a table or other support.

Above the base A is the lantern-body B, within which is arranged the oil-fount C. Through the oil-fount pass tubes D D, which terminate below the body of the lantern in a perforated cup-shaped cavity, formed by the foraminous plate or plates d, that receives and transmits air to and through the tubes D for the purpose of supplying the requisite inside draft to the burner. The upper projecting

ends of the tubes D receive the short tubes *e e* on the under surface of the pyramidal burner-cone E, the inner surface of which is nearly conical in form. This burner-cone consists of an inner and outer shell, which are perforated at the top by the elongated flame-slot *e'*. The lower portion of the outer shell is cut away on each side, so as to present an opening, *e*², having an upper curved outline, as shown, and leading directly to the space between the shells. The short tubes *e e*, which communicate with the main draft-tubes D D, also pass between the inner and outer shells of the burner-cone at each end. Within these short tubes are arranged the perforated cones *e³e³*, which point upward and serve to check or regulate the force of the draft.

In the inner shell of the burner-cone, above the upper end of the tubes *e*, are the foraminous plates *e⁴*, that serve a similar purpose in checking the pressure of air; and in the outer shell, opposite these plates, are perforations *e⁵*, that permit the escape of any undue excess of air, thus insuring the requisite amount of draft without the objectionable effects of an excessive pressure. The lower portion of the burner-cone is provided with a flange, *e⁶*, that nearly covers the cup-like depression at the top of the oil-fount. This depression is formed by an upwardly-projecting band, B', which is closely perforated for the passage of air to the burner and interior of the globe, forming an outer draft, the force of which, however, is broken by the projecting flange *e⁶*, that acts as a guard to prevent too great a pressure.

Attached to the body of the lamp B, at its upper part, is a flaring concavo-convex flange or band, B², that is provided with perforations *b b*, for the passage of air to the vertical perforated band B', air being also permitted to enter at the annular opening between the upper edge of the band B² and a similar band, B³, that is supported upon the upper edge of the vertical band B'. The band B³ forms the lower portion of the chambered globe-holder. When the lamp is exposed to wet weather the perforations *b b* also permit the escape of water that might otherwise collect on the concave surface of the band B².

Within the socket *c* of the oil-fount is fitted the wick-tube F, which is provided with the

usual stem and ratchets, f , for raising and lowering the wick. At the top of the upper flattened portion of this tube is a curved flange, f' , the flaring ends of which, when the burner 5 is in position, fit closely against the upper edges of the inner shell of the latter, thus holding the wick-tube in proper line with the flame-slot and preventing the currents of air passing through the burner from striking the edges of 10 the flame.

Attached to one side of the concavo-convex band B^2 , by means of a suitable hinge, b' , is a convex annulus or band, B^4 , having a central opening that receives a flange or rim on the 15 lower end of the glass globe G , within which projects the upper end of the burner-cone E . The annulus B^4 also supports the upper frame of the lantern surrounding the globe, and is provided with a hasp, b^2 , that is perforated at 20 its end and enters a slot, b^3 , in the band B^2 , where it may be fastened by the hook b^4 , or a suitable padlock, if desired, so as to securely lock the lantern when necessary. When the 25 upper frame of the lantern is closed the convex annulus B^4 rests on the concave flange B^3 , thus forming a chambered globe-holder, within which is the flange or rim at the lower end of the globe.

Extending upward from the annulus B^4 are 30 the flues H , which are preferably three in number and support an attached cap-piece, I , that is surmounted by a perforated dome, K . The flues H are connected by the wire guards or 35 ribs h , which are threaded through the flues and suitably secured within the same, so as to form a continuous frame around the lantern for the protection of the glass globe from external blows or injury.

At the top of the flues H , on their inner sides, 40 are perforations $h' h'$ for the passage of air, the flues thus serving to admit a moderate downward draft to the chambered globe-holder when the lantern is at rest; but are principally useful by furnishing a ready escape for an excessive 45 pressure or draft of air when the lantern is rapidly lowered or in high winds. The flues are connected at their upper ends by an annular band or rib, h^2 , to which is attached the cap-piece I by means of a stout wire, i , that is 50 bent twice at right angles and securely attached to the band h^2 , after passing through suitable perforations $i' i'$ in the edge of the cap-piece I . If desired, the relative position of this wire attachment may be changed by attaching 55 it directly to the cap-piece and forming the perforations $i' i'$ in the band h^2 . This device forms a simple, inexpensive substitute for a hinge that is not liable to get out of order, and allows a perfect freedom of motion to the cap-piece when it is desired to open the lantern for 60 introducing or removing the globe. It also enables the cap-piece to fit more closely upon the frame.

The cap-piece I is provided with a spring- 65 hasp, I' , that engages with a spring-staple, I^2 , which is attached at its upper end to the outer side of one of the flues H , the lower end of the

staple being bent inward at a right angle to enter a small slot in the flue, and then again bent in an upward direction to form a stop 70 that limits its outward spring. When the hasp I' is engaged with the spring-staple I^2 the cap-piece is held firmly in place, but may be further secured, if desired, by means of a small padlock attached to the staple on the outer side 75 of the hasp. When it is desired to release the hasp for the purpose of raising the cap-piece, a slight inward pressure upon the staple will be sufficient to disengage the parts.

The upper end of the globe G , when in position, presses against a horizontal annular flange, l , in the interior of the perforated dome K , and is thus held firmly in place. This dome is provided with the usual perforations $k' k'$, 80 for the passage of heated air, and also has a 85 bail, L , by means of which the lantern is handled.

From the foregoing description the operation and advantages of my improved lantern and globe will be readily understood.

The draft passing upward from the base of the lamp through the tubes on each side of the oil-fount to the burner and globe is checked and rendered even and steady by means of the perforated plates at the lower ends of the main tubes and by the perforated cones in the small connecting-tubes and foraminous plates above the latter on the inner shell of the burner-cone. By means of the vertical perforated band that connects the top of the oil-fount with the chambered globe-holder the interior of the burner and globe is still further supplied with fresh air in a finely-diffused state, the pressure being moderated by the perforations through which it is made to pass, and an exit for any 100 excess being afforded through the flues that lead up on the outer side of the globe to the cap-piece supporting the perforated dome, through which the heated air and products of combustion finally escape.

The peculiar construction of the burner is such that it is enabled in a still atmosphere to burn oils having a test of 150° without the necessity of using a globe or chimney of any kind, giving a clear, safe light, and in using 115 oils having a test no higher than 150° any globe that will fit the lantern may be used with the burner as a protection to the flame in the open air. When using mineral, sperm, or oil of 300° test a globe is needed that will concentrate the inflowing air in the immediate vicinity of the flame.

The peculiar construction of my improved globe above described is such that by means of its base flaring outward from the contracted portion or neck g , and adapted to fit over the burner and correspond with the perforated band below the chambered globe-holder, a draft-current of uniform strength is at all times drawn into the lantern, and the globe is 130 prevented from becoming unduly heated.

In rapidly changing the position of the lantern by raising or lowering it the tendency to unequal pressure thereby developed is obviated

by the flues and construction of the burner and wick-tube, so that the flame is prevented from dipping or being extinguished, the edges of the flame being protected especially by the 5 peculiar flange at the top of the wick-tube, which corresponds closely with the flame-slot in the apex of the burner-cone.

It will be understood that I do not confine myself to the precise details of construction 10 herein described, as the parts may be combined in a number of ways and still kept within the limits of the invention.

What I claim is—

- 15 1. The combination, with a lantern frame and fount having air tubes or passages covered at their lower ends by foraminous plates, and a wick-tube provided at its upper end with a curved flange, of a burner-cone consisting of an inner and outer shell having a flame-slot 20 that corresponds with the flange of the wick-tube, and provided with the described openings and tubes having perforated cones adapted to moderate the draft, substantially as described.
- 25 2. The combination, with an oil fount and burner, of a chambered globe-holder and flues leading therefrom on the outer side of the globe, to afford a means of escape for an excess of air, and thereby preventing the flame from

dipping or being extinguished or the parts unduly heated, substantially as set forth. 30

3. The combination, with a lamp-fount, burner, and chambered globe-holder having flues leading therefrom, of a globe having a flaring base and contracted neck, whereby 35 it is adapted to concentrate the draft in the vicinity of the flame without becoming excessively heated, substantially as described.

4. The combination, with the lamp body and globe, of a hinged frame composed of the upper convex band of the globe-holder, flues leading therefrom and supporting an attached cap-piece, and circular guards or ribs connecting said flues and adapted to protect the globe from external injury, substantially as specified. 40

5. The combination, with the cap-piece and upper rib of a lantern-frame, of an attachment composed of a wire bent twice at right angles and adapted to support said cap-piece when raised or thrown back, substantially as set 45 forth. 50

In testimony whereof I have hereunto set my hand in the presence of two subscribing witnesses.
